[57] CLAIM

The ornamental pull for drawers, doors or the like, as shown and described.

DESCRIPTION

FIG. 1 is a front perspective view of a pull for drawers, doors or the like showing our new design;

FIG. 2 is a front perspective view thereof showing an opposite end thereof with the broken lines of a drawer or door being for illustrative purposes only and forming no part of the claimed design;

FIG. 3 is a front elevational view thereof;

FIG. 4 is a rear elevational view thereof;

FIG. 5 is a right end elevational view thereof;

FIG. 6 is a left end elevational view thereof;

FIG. 7 is a top plan view thereof;

FIG. 8 is a bottom plan view thereof;

FIG. 9 is a front perspective view of a second embodiment of the design of FIG. 1;

FIG. 10 is a front perspective view of the end opposite that shown in FIG. 9 with the broken lines of a drawer or door being for illustrative purposes only and forming no part of the claimed design;

FIG. 11 is a front elevational view of FIG. 10;

FIG. 12 is a rear elevational view of FIG. 10;

FIG. 13 is a right end elevational view of FIG. 10;

FIG. 14 is a left end elevational view of FIG. 10;

FIG. 15 is a top plan view of FIG. 10;

FIG. 16 is a bottom plan view of FIG. 10.
